UNITED STATES PATENT OFFICE.

JOHN E. HILL, OF BERKELEY, CALIFORNIA.

SOLE CLAMP.

Application filed October 13, 1921. Serial No. 507,476.

To all whom it may concern:

Be it known that I, JOHN E. HILL, a citizen of Finland, and a resident of Berkeley, county of Alameda, and State of California, 5 have invented a new and useful Sole Clamp, of which the following is a specification.

My invention relates to apparatus for repairing shoes and an object of the invention is to provide a device for clamping the sole 10 to the bottom of a shoe while a layer of adhesive for attaching the sole is setting.

My invention possesses other objects and features of advantage, some of which, with the foregoing, will be set forth in the following description of my invention. It is to be understood that I do not limit myself to the showing made by the said description, as I may adopt variant forms of my invention 15 within the scope of the claims.

20 In the drawings, Fig. 1 is a perspective view of my device applied to a shoe. Fig. 2 is a vertical sectional view taken longitudinally thru the center of my device and showing a shoe held therein.

25 In general terms the device of my invention comprises a pressure plate adapted to fit over the sole which is secured to the bottom of a shoe, and faced with a resilient pad for evenly distributing the pressure over all 30 portions of the sole. Means are provided for supporting the inner surface of the shoe bottom and clamping means are also provided for pressing the supporting plate and the pressure plate together so that the sole to 35 which adhesive has been applied is held with resilient pressure in proper position until the adhesive sets.

More particularly my device comprises a 40 supporting plate 2 adapted to be inserted into the shoe. A number of these plates varying in size to adapt them for use with different sizes of shoes are provided.

45 After the plate is inserted into the shoe the shoe is placed on a last 3 of the usual type. The last acts as a backing for the supporting plate. Of course a block similar in form to the end of the last could be used for a backing but since a last is the most convenient and is a part of every shoemaker's outfit, its use is preferred.

50 A pressure plate 4 of sufficient size to cover the ordinary sizes of half soles is provided with a resilient pad 6 attached thereto in any suitable manner as by loops of wire 7.

A heavier plate or block 8 is fixed to the back 55 of the pressure plate and rotatably secured therein is a screw 9 which is threaded thru one side of the square clamp ring 11 of such proportions as to permit it to be inserted over the toe of the shoe as shown in Fig. 2. 60 The opposite side of the clamp ring is provided with a short plate 12 padded with some soft material such as felt 13 to prevent injury to the surface of the shoe.

In order to secure a half sole to the bottom of a shoe with my device the sole is reduced to desired size and adhesive applied to the two parts and the sole pressed into place. My clamp is then opened and after positioning the shoe on the last with the supporting plate 2 in position, is pushed over the toe in the position shown in Fig. 2 and the screw 9 turned down to apply pressure to the sole. The resilient pad secures an even application 75 of pressure over all the surface of the sole and especially around the edges which the resilient pad somewhat overhangs. After sufficient time has elapsed for the setting of the adhesive the clamp is removed and the sole is bound to be permanently united 80 without the use of nails or stitches.

I claim:

1. A device for clamping a sole to a shoe comprising a rigid plate for supporting the inside bottom surface of the shoe, a resilient pad for engaging the sole, a pressure plate for backing the pad, means from which said plate is separable arranged on the inside of the shoe for backing the supporting plate, and clamping means adjustable over the toe 95 of the shoe for pressing the parts together.

2. A device for clamping a sole to a shoe with a last therein, comprising a plate separate from said last and conforming to the shape of and adapted for supporting the inside bottom surface of the shoe, a continuous ring for enclosing the toe of the shoe and the plate, a resilient pad for engaging the sole and arranged to overlap the edges thereof, a pressure plate secured to said ring and conforming to the shape of and arranged for backing said pad, and a second pad and plate secured to said ring and arranged to engage the top surface of the shoe upper.

In testimony whereof, I have hereunto set 100 my hand.

JOHN E. HILL.
